UNITED STATES PATENT OFFICE.

WILLIAM G. DUNN, OF CLARINDA, IOWA.

CONTROLLING MEANS FOR RADIO SETS.

Application filed April 2, 1925. Serial No. 20,254.

This invention relates generally to radio apparatus, and particularly to mechanical means for controlling or tuning radio sets. The invention is especially adapted for use in connection with radio receiving sets, but it is to be understood that it is not necessarily limited to use in this connection.

Recently there has been devised a very efficient type of tuned radio frequency receiving set in which tuning is effected by the adjustment of the dials of three variable tuning devices. Such sets have become very popular, but they are not extremely easy to tune because they are very selective and since the tuning is sharp, they must be tuned very carefully to obtain the best results. In sets of this character which are properly designed and balanced, all three dials must be set at or very nearly at the same place to tune into a particular station. Up to the present time, this has always been done by adjusting or setting one dial after another, but the present invention eliminates the necessity for this procedure because it is a mechanism whereby all three dials of a set of the character mentioned may be adjusted simultaneously.

According to the invention, the shafts of the rotors of the variable tuning devices extend through openings in the panel of the set and are provided at their front ends in front of the panel with dials, as usual, but in addition to this, the dials are connected in such a manner that they will be turned simultaneously or in unison when any one of them is adjusted by the operator. In some cases, it is advisable and sometimes necessary to adjust one or more of the dials independently of the others, so that according to the invention, adequate provision has been made for this.

The invention is hereinafter more fully described by reference to the accompanying drawings which form a part of this specification.

In the accompanying drawings:—

Fig. 1 is a front elevation of a three dial radio receiving set equipped with mechanism constructed in accordance with the present invention;

Fig. 2 is a horizontal sectional view taken substantially on the plane indicated by line 2—2 of Fig. 1;

Fig. 3 is a vertical sectional view of a portion of the set taken substantially on the plane indicated by line 3—3 of Fig. 1;

Fig. 4 is a view similar to Fig. 3 but showing a different position of the parts;

Fig. 5 is a front elevation of the mechanism associated with one of the dials of the set, but showing the dial removed;

Fig. 6 is a front elevation of the same type of radio set illustrated in Fig. 1 but showing a different embodiment of the invention;

Fig. 7 is a horizontal sectional view taken substantially on the plane indicated by the line 7—7 of Fig. 6;

Fig. 8 is a transverse sectional view taken on the plane indicated by the line 8—8 of Fig. 6; and

Fig. 9 is a view similar to Fig. 8 but showing a still further embodiment of the invention.

Referring more particularly to the drawings, the numeral 1 designates the front panel of a radio receiving set of the above-described type, and the numerals 2 designate the dials located at the front of the panel 1, which are adjusted to tune the set. These dials 2 are fixed upon the front ends of the rotor shafts 3 of the variable tuning devices of the set. As shown, the front ends of the shafts 3 extend through apertures 4 in the panel 1, while the rotors 5 and other parts of the tuning devices 6 are located back of the panel 1.

Turnably mounted upon the shafts 3, preferably in front of the panel 1 and back of the dials 2, are toothed disks or pinions 7. These are connected for simultaneous movement by some suitable means such as by a rack bar 8 slidably mounted in guides 9 carried by the panel 1.

Secured to the disks or pinions 7 and extending from the same across the back of the dials 2, are resilient arms 10. Adjacent their free ends, these arms 10 carry friction shoes 11 which are normally in engagement with the backs of the dials 2 adjacent the peripheries of the latter. These shoes 11 when in engagement with the backs of the dials 2 couple the dials to the arms 10 and to the disks or pinions 7 through the medium of such arms, and since the disks or pinions 7 are connected by the rack 8, all three dials are connected for simultaneous movement or adjustment. It will therefore be seen that the adjustment of any one dial will simultaneously and correspondingly adjust the others, so that although the receiving set has three variable

2
tuning devices, it may be regarded as a set having a single control.

In some cases, it may be advisable for the different tuning devices to be tuned independently, and in other cases, this may be found to be necessary, so rotatably mounted upon the free ends of the arms 10 are vernier knobs 12. Normally, these knobs 12 are out of engagement with the dials 2, but may be easily depressed and brought into engagement with the same. When the knobs 12 are depressed so as to be brought into operative engagement with the dials 2, the arms 10 will be likewise depressed or sprung rearwardly, causing the shoes 11 to be moved out of engagement with the rear surfaces of the dials 2. Then, by turning the particular knob 12 which has been depressed, the corresponding dial 2 will be turned, and since the corresponding arm 10 will remain stationary, no adjustment will be made in the other tuning devices.

In order to prevent any of the arms 10 from being swung when they are depressed at the time the vernier knobs 12 are used, such arms are provided adjacent their free ends with additional friction shoes 13. These shoes 13 are arranged so that they will engage the front face of the panel 1 when the arms 10 are depressed.

While the friction shoes 11 and 13 are embodied in the preferred construction, yet their use is not absolutely necessary, for substantially the same results may be obtained by constructing the mechanism as shown in Figs. 6, 7 and 8. In this case, the vernier knobs 12' are always in engagement with the dials 2, and the arms 10' need not be resilient. When independent adjustment of any of the dials 2 is desired, that may be effected merely by turning the particular knob 12', while holding the corresponding arm 10' against swinging movement.

These same views also show how the pinions 7 may be replaced by grooved disks or pulleys 7' and connected together for simultaneous movement by belts 8' to correspond with the rack bar 8.

Figure 9 illustrates a further embodiment of the invention. In this case, each pinion 7" is located back of the panel and is rigid with a substantially flat disk 14 disposed in front of the panel, the hub of this unitary member extending through the hole in the panel. The shaft 3 extends through the bore of the hub of the unitary member just referred to and carries at its free end a turning knob 2". Extending radially from this knob is an arm 10" to the free end of which is rotatably mounted a vernier knob 12" having a portion permanently in engagement with the disk 14 adjacent the periphery of the latter. By turning any of the knobs 2" or the disks 14 of this embodiment, all of the shafts 3 will be turned in unison,

but independent adjustment of any one of the shafts 3 may be obtained by holding the corresponding disk 14 stationary and rotating the corresponding knob 12". When this is done, the portion of this knob which bears upon the periphery of the disk 14 will travel along the periphery of such disk and movement will be imparted to the shaft.

From the foregoing description taken in connection with the accompanying drawings, the construction, operation, use and advantages of the invention will be readily understood, so that further explanation is unnecessary.

It is obvious that numerous changes in form, proportion, details of construction and in the combination and arrangement of parts, may be made without departing from the spirit and principle of the invention and without sacrificing any of the advantages thereof, so that it is to be understood that such may be done within the meaning and scope of the appended claims which define the novelty contained in the invention. It will also be understood that the invention is not limited to use in connection with radio sets of the character or type illustrated in the drawings and specifically described heretofore, or that the number of tuning devices is material, for it is obvious that the invention may be used in connection with various kinds of radio sets having two or more variable tuning or other adjustable devices.

I claim:

1. An adjusting means for a plurality of instrument shafts, said means comprising two members for each instrument, one rotatable with respect to the shaft and the other secured to the shaft, means for simultaneously rotating the rotatable members, and a driving connection from the rotatable member of any instrument to the shaft-carried member of such instrument, said driving connection having finger-operated means for simultaneously holding the rotatable member against turning and effecting an adjustment of the shaft-carried member.

2. An adjusting means for a plurality of instrument shafts, said means comprising a disk member and an adjustment carrying member for each instrument, the two members being co-axially mounted, one member being secured to the shaft and the other rotatable with respect thereto, and means for simultaneously rotating the rotatable members, said carrying members having adjusting devices for co-action with the disks to effect relative adjustment thereof, said simultaneously rotated members having frictional driving connections with the shaft-carried members to effect rotation of the latter simultaneously when said simultaneously rotated members are driven.

3. In an instrument adjusting means, a disk, a carrier mounted co-axially therewith

and free to rotate with respect thereto, a shoe on the carrier normally contacting with the disk to rotate the latter when the carrier is rotated about its axis, and a disk-adjusting device mounted on the carrier and normally spaced from the disk, said carrier being movable to move the shoe from the disk and to simultaneously engage said disk-adjusting device with said disk.

10 4. In a device of the class described, the combination of a plurality of turnable instrument shafts, manually operative turning elements for said shafts and fixed thereto, pinions turnably mounted upon said shafts, a rack bar engaging said pinions and connecting the same for simultaneous movement, and members carried by said pinions and engaging said elements to impart motion from one to the other, said members being movable relatively to said elements to permit the latter to be adjusted independently.

5. In a device of the class described, the combination of a plurality of turnable instrument shafts, dials fixed upon said shafts for turning the same, disks turnably mounted upon said shafts, means connecting said disks for simultaneous movement, arms extending from said disks across said dials, and friction shoes carried by said arms and engaging said dials and coupling the two together, said shoes being releasable from said dials by the depression of said arms to permit said dials to be independently adjusted.

30 6. In a device of the class described, the combination of a plurality of turnable instrument shafts, dials fixed upon said shafts for turning the same, disks turnably mounted upon said shafts, means connecting said disks for simultaneous movement, arms extending from said disks across said dials,

friction shoes carried by said arms and engaging said dials and coupling the two together, said shoes being releasable from said dials by the depression of said arms to permit said dials to be independently adjusted, and normally inoperative vernier knobs for said dials rotatably mounted upon said arms, said knobs being adapted when depressed to operatively engage said dials and simultaneously depress said arms and release said shoes from said dials.

7. In a radio set, the combination of a plurality of turnable instrument shafts, the front ends of said shafts extending to the front of the panel through openings in the same, dials fixed upon the front ends of said shafts in front of said panel, disks turnably mounted upon said shafts, means connecting said disks for simultaneous movement, arms extending from said disks across the backs of said dials and in front of said panel, friction shoes carried by said arms and engaging said dials and coupling the two together, said shoes being releasable from said dials by the depression of said arms to permit said dials to be independently adjusted, normally inoperative vernier knobs for said dials rotatably mounted upon said arms, said knobs being adapted when depressed to operatively engage said dials and simultaneously depress said arms and release said shoes from said dials, and additional friction shoes carried by said arms to engage the front of said panel and prevent said arms from swinging when the same are depressed.

8. A structure as specified in claim 3; together with holding means for said carrier brought into play by the aforesaid movement thereof.

In testimony whereof I have hereunto affixed my signature.

WILLIAM G. DUNN.
